Cash & Co.

UNITED STATES PATENT OFFICE.

GEORGE W. WILLIAMS, OF BLUE RIDGE, MISSOURI.

HAME-TUG.

SPECIFICATION forming part of Letters Patent No. 466,478, dated January 5, 1892.

Application filed May 20, 1891. Serial No. 393,390. (No model.)

To all whom it may concern.

Be it known that I, GEORGE W. WILLIAMS, a citizen of the United States, residing at Blue Ridge, in the county of Harrison and State of Missouri, have invented a new and useful Combined Trace-Buckle and Hame-Tug, of which the following is a specification.

This invention relates to a combined trace-buckle and hame-tug; and the objects in view are to provide a device of this class in a cheap and simple manner and one possessing great strength, and by its construction to avoid the necessity of using the usual leather loops and to maintain the draft in a straight line.

Other objects and advantages of the invention will appear in the following description, and the novel features thereof will be particularly pointed out in the claim.

Referring to the drawings, Figure 1 is an elevation of my combined hame-tug and trace-buckle, the same being in position. Fig. 2 is a longitudinal sectional view. Fig. 3 is a detail in perspective of the buckle.

Like numerals of reference indicate like parts in all the figures of the drawings.

1 designates the tug-strap, which terminates at its rear end in a loop or eye 2 and is provided with the metal thimble or bushing 3, through which and the side bars 4 of the buckle-frame passes a bolt 5. The side bars of the buckle-frame are connected near their front and rear ends by keepers 6 and 7, respectively, and lie against the leather shield 8, connected to the tug-strap. At their upper and lower sides the side bars have keepers or loops 9 designed to engage with the back-band and girth of the harness.

10 designates a pair of U-shaped bails, the terminals of which are inwardly bent and are pivotally engaged, as at 11, with the opposite side bars. These bails pass through a locking-bar 12 and are adapted to swing with the bar toward and away from the side bars. The locking-bar 12 is chamfered or undercut at its

45 rear end so as to fit upon and overlap the rear keeper 7, and when in such position takes between a pair of eyes 13, located upon said keeper, and may be locked in this position by a pin 13, passed through the eyes and over the 50 locking-bar 12.

14 designates the trace, the same being of ordinary construction and provided at intervals, agreeing in distance apart with lugs 15 upon the under side of the locking-bar 12, with holes 16. The front end of the trace is 55 passed through a slot 17 in the rear end of the shield 8, thence through the rear keeper 7, over the intermediate web portion connecting the locking-bar, and through the keeper 6. The trace is first adjusted in the buckle-frame, the locking-bar being swung outwardly, after which said bar is swung inwardly upon the keeper 7, so that its lugs 15 will pass through two adjacent holes 16 of the trace, after which the locking-pin is passed through 60 the eyes 13 and the connection is completed. It will be seen that the draft between the tug and trace is maintained in a straight line, and that while the trace-buckle is exceedingly simple in its construction and easily 65 and quickly operated, either to connect or disconnect the trace, the two lugs will serve to double the strength of those buckles employing but one tongue or lug.

Having described my invention, what I 75 claim is—

The herein-described improved trace-buckle, comprising the opposite longitudinal side bars connected at their front and rear ends by the keepers 6 and 7 and at the front 80 end having the bolt for engaging the hame-tug, the opposite eyes 13, mounted upon the rear keeper, the U-shaped bails having inwardly-turned ends pivoted in the side bars, the locking-bar 12, through which the bails 85 loosely pass, terminating at its front end in an undercut keeper-overlapping portion and provided upon its inner side with a pair of trace-engaging lugs, and a locking-pin passed through the eyes and across the outer side of 90 the locking-bar, substantially as specified.

In testimony that I claim the foregoing as my own I have hereto affixed my signature in presence of two witnesses.

GEORGE W. WILLIAMS.
